INVENTOR:

Rudolph Ledig,
BY Fred C. Graentzel, ATTY.

UNITED STATES PATENT OFFICE.

RUDOLPH LEDIG, OF NEWARK, NEW JERSEY.

DESIGN FOR A COUNTER FOR BAR-ROOMS.

SPECIFICATION forming part of Design No. 22,399, dated May 2, 1893.

Application filed February 27, 1893. Serial No. 463,958. Term of patent 14 years.

To all whom it may concern:

Be it known that I, RUDOLPH LEDIG, a citizen of the United States, residing at Newark, in the county of Essex and State of New Jersey, have invented and produced a new and original Design for a Counter for Bar-Rooms, &c., of which the following is a full, clear, and exact description of the same, reference being had to the accompanying drawings, forming a part thereof.

My invention is for a new and original design for a counter for bar-rooms, &c., the leading feature of which is the front side thereof having a paneled space which is outwardly curved at the top and inwardly curved at the bottom, as shown in the accompanying drawings, in which:—

Figure 1 is a front perspective view of a counter for bar-rooms, &c., clearly illustrating the arrangement of the outwardly and inwardly curved panel; and Fig. 2 is an end view of the counter.

The drawings are deemed sufficient to illustrate the leading features of my design.

In the drawings, the counter *a* is shown as having a panel *a'* which is outwardly curved

at the top, as at *a²*, and inwardly curved at the bottom, as at *a³*. At the sides of said outwardly and inwardly curved panel in the front of the counter are the straight panels *b*, forming with the top shelf of the counter an offset *b'* and with the curved panel, the straight off-set *a⁴*. At the sides of said panels *b*, are the columns *c*, which are surmounted by curved brackets *c'* acting as supports for the 35 fender *d*. These parts practically form the upper finish of the counter.

The essential feature of my design is the arrangement of the outwardly and inwardly curved panel *a*.

Having thus described my invention, what I claim, and desire to secure by Letters Patent, is—

The design for a counter for bar-rooms, &c., substantially as herein shown and described. 45

In testimony that I claim the invention set forth above I have hereunto set my hand this 25th day of February, 1893.

RUDOLPH LEDIG.
